AIR CONDITIONING DEVICE

Fred M. Opitz, Milwaukee, Wis., assignor to Hexcel Radiator Company, Milwaukee, Wis., a corporation of Wisconsin

Application October 4, 1932, Serial No. 636,164

20 Claims. (Cl. 219—39)

This invention relates to air conditioning devices, and more particularly to portable conditioning devices adapted to be installed in rooms or similar enclosures in homes and office buildings, or the like.

In the preferred embodiment of the invention, I provide a conditioning unit for heating and humidifying the air in a room or similar enclosure comprising a receptacle containing water and provided with an electrical heating element for heating the water. A motor driven fan is adapted to draw air in over the surface of the heated water, where the air is humidified and heated by the steam or vapor rising from the water, and the fan then discharges this air into the room. An automatic switch, operative only when the receptacle contains water, is provided for operating the fan, and also controls the operation of the heating element to prevent over-heating thereof when the water has all been evaporated.

The provision of a conditioning device adapted to heat the air as well as humidify it by the addition of steam or vapor thereto is distinctly advantageous as compared to a device wherein the air is passed through a spray of cool water and must entrain water particles therein. In the latter type of device, little water can be added to the air because of the low temperature of the water and the relatively large size of the droplets. It is apparent that air can absorb more moisture if heated than if cooled, due to the difference in relative humidity of the air. The energy necessary to heat the water is offset by the reduction in the fuel consumption for heating the room, since the humidified air need not be reheated, as is necessary in connection with devices using a cool water spray or the like.

I have found that with my device sufficient moisture can be imparted to the air in the room or enclosure if the device is operated only two hours in the morning and two hours in the afternoon, under average conditions, since for the normal size of room about two gallons of water added to the air per day is sufficient. It is to be understood, however, that the device may be used continuously, if desired, or to satisfy any condition that may be required in a given situation.

The operation of the device is automatic, after it has once been connected to a convenient wall socket or the like, as it will start automatically when filled with water, and will stop automatically when the water has been exhausted. This is accomplished by means of a float controlled switch which controls the operation of the fan and heating element. If desired, a manual control may be provided for either the fan or heating element, or both, where it is desired to operate the device independently of the water supply. In addition, the device is provided with a secondary

control switch connected to the heating element, by means of which the temperature of the heating element may be controlled to provide slow evaporation of the water, or rapid evaporation of the water, as desired.

It is therefore an object of the present invention to provide a unitary air conditioning device which is portable, neat in appearance, and efficient in operation. Combined with the feature of portability is the compactness of the construction, with all of the parts hidden from view and enclosed by an attractive casing having a handle thereon for facilitating transportation of the device.

A further object of the present invention is the provision of a water receptacle within the unit which may be easily filled, and which is provided with automatic means for indicating when sufficient water has been added thereto.

Another object of the present invention is to provide a device which is automatically put into operation as the water is added, and which is automatically shut off when the water has been evaporated, thus preventing burning out or over-heating of the resistance.

A still further object of the present invention is the provision of a unit of this type which does not detract from the appearance of the room or enclosure where it is placed and which, while requiring somewhat more energy for its operation than a cold-spray type of conditioning unit, effects economy of operation because of the reduction in energy necessary to heat the room, since the device itself performs a part of this function. In connection with this feature, the provision of a device utilizing the principle of hot water heating, with humidification by absorption of steam or vapor into the air stream, instead of the absorption of water particles, eliminates condensation and provides a more efficient and uniform humidifying of the room air. The amount of water vapor absorbed by heated air is far greater than that absorbed by cooled air, and therefore the unit need not be operated for as long a period as devices using the cold spray principle.

Other objects and advantages of the present invention will appear more fully from the following detailed description, which, taken in connection with the accompanying drawings, will disclose to those skilled in the art the particular construction and operation of a preferred embodiment of the invention.

In the drawings:

Figure 1 is a rear perspective view of the assembled unit;

Figure 2 is a front elevational view of the unit;

Figure 3 is a sectional elevational view, taken substantially on the line 3—3 of Figure 2, and disclosing in detail the mounting of the fan within the casing;

Figure 4 is a sectional view taken substantially on the line 4-4 of Figure 3, looking in the direction indicated by the arrows;

Figure 5 is a rear perspective view of the unit 5 with the outer casing removed;

Figure 6 is a detail sectional view of the float mounting and associated switch, taken substantially on the line 6-6 of Figure 4; and

Figure 7 is a detail plan view of the heating 10 element disposed in the water receptacle.

Referring now in more detail to the drawings, in Figure 1 I have disclosed the completely assembled unit, having a rear plate indicated generally by the numeral 10, a front plate indicated 15 generally by the numeral 11, and having a casing 12 adapted to space the rear and forward plates apart and forming a base for the unit. It will be noted that the plates 10 and 11 extend above the upper limits of the spacing member 12, and a 20 suitable handle 13, secured between the plates by means of a through bolt or screw member 14, is provided for facilitating transportation of the unit.

The rear plate 10 is provided with a substantially circular grille portion 15, which is provided with a plurality of radially extending openings 16 adapted to provide ventilation for the fan motor 17. The grille 15 may be formed integrally with the plate 10, or may be a separate member secured thereto, and is provided with a laterally offset portion 18, having a circular opening formed therein for receiving a sight glass 19 through which the operation of the float-controlled switch 20 may be observed.

35 The plate 10 is also provided with a rearwardly extending offset portion 22 which fits about a corresponding portion of the inner casing or water receptacle, and which provides a readily accessible means for filling the water receptacle.

40 The casing or plate 10 is also provided with a cut-out portion 23 at the bottom thereof, which is adapted to provide an opening for leading in the electrical conduit member 24, which is connected to a suitable source of electrical current. Projecting through the plate 10 is a control switch 45 indicated generally at 25, which provides for control of the heating element and operation of the fan. The casing member 12 is secured to the plates 10 and 11 by means of screws 27 which

50 thread into suitable bracket members 28 carried by the plates 10 and 11, as shown in detail in Figure 4. Suitable rubber covered studs or screws 29 are threaded into the base 30 of the casing member 12, and extend up and are threaded into 55 brackets or lugs 31 carried by the plates 10 and 11 for forming supporting means for the unit and for additionally securing the plates to the casing member 12.

Considering now in detail in Figure 2, the plate 60 11 is provided with a circular opening or cut-out portion indicated at 33, which provides the outlet for the air drawn through the unit. The plates 10 and 11, together with the casing member 12, may be finished in any desired style, such 65 as by being plated, provided with a satin finish, or provided with a stamped design or the like. The configuration of the casing of the unit somewhat resembles that of the so-called "Cathedral" type of radio receiving set, and, when finished 70 properly, enhances the appearance of a room rather than detracting therefrom, as has been the case with prior types of home conditioning units.

Considering now in detail Figures 3, 4 and 5, I 75 provide a water receptacle or housing of generally

rectangular shape and having a rounded upper portion, indicated generally by the numeral 35. The housing 35 is provided with side walls 36 and 37, and with a bottom wall 38. Extending outwardly from the rear wall 36 is a laterally 5 and vertically extending spout portion, of generally triangular shape, indicated at 39, which provides for admitting water to the receptacle. The spout portion 39 is provided with an opening 40 adjacent its upper end, which opening is closed 10 by means of a perforated cover member 41 hingedly secured to the extending spout 39 by means of a pivot bolt 42. The cover 41 is raised when it is desired to pour water into the receptacle, but is normally maintained in closed position 15 during the operation of the device, and provides an inlet opening for the air entering the unit.

The entire casing 35 is enclosed by suitable heat insulating means, which may comprise asbestos, pressed mineral wool, heavy cardboard, or 20 the like, and which is preferably glued or otherwise secured to the outer surface of the walls 35, 36, 37 and 38. This insulation is indicated generally by the numeral 45, and entirely surrounds and encloses the housing. At the bottom portion 25 of the casing a flat piece of asbestos or similar insulating material is provided, indicated at 46, to space the device from the bottom wall 30 of the spacing or casing member 12.

The housing 35 is supported within the casing 30 at its top and bottom, there being a supporting lug 48 riveted or otherwise secured to the wall 35 of the casing, as by means of rivets 49, and which is provided with an offset extending portion adapted to be secured to the casing member 12 35 by means of the bolt 50. At its lower end, a second supporting lug 51 is welded or otherwise secured to the bottom wall 38 of the housing 35, and is secured to the bottom wall 30 of the casing member 12 by a bolt 52. This serves to position 40 the casing 35 with its associated insulation 45 in rigid position with respect to the casing member 12, and consequently with respect to the plates 10 and 11.

Disposed in the upper central portion of the 45 housing 35 is a cylindrical sleeve member 54, which extends from the rear wall 36 to a point approximately coplanar with the insulation 45 carried upon the front wall 37 of the housing. This sleeve is provided with a plurality of circumferentially disposed openings 55 for providing an outlet for the interior 56 of the casing 35 to permit the air drawn into inlet 40 to pass through the outlet 33 under the influence of the fan 57 mounted by means of the collar 58 upon shaft 59 55 of the fan motor 17. An annular retaining washer or ring member 60 is suitably secured to second cylindrical sleeve member 61 carried at the forward end of the sleeve member 54. The ring member 60 is provided with a circular opening 62 60 which is concentric with the outlet opening 33 formed in the plate 11.

A cup-shaped supporting member 63 is provided in the interior of the sleeve member 54 at the rear portion thereof, and has its flanged 65 bottom portion 64 extending normal to and slightly to the rear of the openings 55. Suitable insulation 65 is provided upon the cup-shaped member 63 and its bottom 64. A plurality of threaded screws 66 are adapted to support the fan motor 70 17 in position upon the flanged portion 64 of the member 63, and dispose the fan concentrically with respect to the sleeve member 54. The fan motor is thus held securely in position and the fan is adapted to rotate in a clockwise direction 75

to draw air through the openings 55 and force it outwardly through the opening 33 formed in the plate 11.

A suitable grille, indicated at 10, is secured over the forward end of the sleeve member 81 by means of a plurality of screws 71, which are threaded into extending boss portions 12 formed on the forward wall 31 of the casing 35. The grille 10 may be formed of wire mesh or the like, and is provided for the purpose of preventing contact with the rotating fan 51, and also for preventing the entry of paper or similar debris into the fan chamber. It also masks the view of the fan, thus enhancing the appearance of the unit.

A cylindrical hollow float 15 is disposed within the chamber 56 of the housing 35, and is mounted upon a shaft 76 by means of the extending connecting member 11. The shaft 76 is provided with a bearing support in each of the walls 36 and 37, and is provided with an enlarged head portion 78 upon the outer surface of the wall 37 for aligning the shaft with respect to the walls. The insulation 45 is cut out, as indicated at 19, to provide free movement of the head 78 upon rotation of the shaft 76. At its opposite end, the shaft 76 is provided with a collar member 80, secured thereto by means of the set screw 81 and having a pair of laterally extending spring finger members 82 adapted to receive the automatic switch 20.

The switch 20 comprises a glass-sealed tube, preferably evacuated, which has sealed therein a pair of contacts indicated at 85 and 86. These contacts have terminal portions extending through the glass, and sealed in position therein, and are connected by means of the conductors 87 and 88 to the power supply. Upon rotation of the shaft 76, the switch 20 is also rotated, and the globule of mercury 89 is rolled into contact with the contacts 85 and 86, thus closing the circuit. The shaft 76 is rotated by means of the float 75 rising and falling in accordance with the water level in the chamber 56. Suitable stops 90 and 91 are provided for limiting the movement of the float 75, the stop 90 being positioned upon the side wall of the casing 35 so that when the float is in its uppermost position the switch will be closed. When the float reaches the position determined by the stop 91, the mercury will roll away from the contacts 85 and 86, and thus will break the circuit. At this position, the water level is just sufficient to cover the heating elements. Because of the evacuated condition of the switch, the switch can be operated innumerable times without affecting the condition of the contact members, since no corrosion or pitting occurs.

Considering now the heating element for the receptacle 35, this element, as shown in detail in Figure 7, comprises two U-shaped members 92 and 93, which are provided with a supporting web 94. The members 92 and 93 are generally rectangular in section, as shown in Figure 3, and are preferably hollow to receive the resistance elements 95 and 96, the resistance element 95 extending through the U-shaped member 92, and the resistance element 96 extending through the U-shaped member 93. These may be wire wound resistance strips, metal strips, or carbonaceous elements, as desired. Suitable insulation is provided between the members 92 and 93 and the resistance strips 95 and 96 extending therethrough, this insulation comprising sheets of mica, or other suitable means, indicated by the numeral 97 in Figures 3, 4 and 7.

The elements or members 92 and 93 are supported upon a plate member 98, having the flanged portions 99 receiving these members. A suitable gasket or bushing member 100 is disposed upon the inner surface of the side wall of the receptacle 35, and slidably receives the flanged portions 99 of the plate 98 to support the elements in position. A gasket 101 is interposed between the surface of the plate 98 and a supporting frame member 102. The supporting frame member 102, as indicated in Figure 5, is secured to the member 100 by means of screws 103 passing therethrough. This serves to support the heating elements 92 and 93 in position within the chamber 56.

It will be noted that one extending end of each of the resistance elements 95 and 96 is connected together by a sleeve member 105 having the bolt 106 passing therethrough. The opposite ends of the resistance elements 95 and 96 are each provided with a separate terminal bolt 107 and 108, respectively. It will thus be apparent that the resistance element can be connected at one point to utilize either one of the resistance strips 95 and 96. For example, if the element is connected to use one of the elements, as for example, element 95, the terminals 106 and 107 will be provided with conductors leading to a source of current supply. If it is desired to connect only the inner element 96, the terminal bolts 106 and 108 will be utilized. Thus, either a high or a low temperature may be produced by the heating elements 92 and 93, thus providing for slow or rapid evaporation of the water in the chamber 56.

Referring now in detail to the operation of the control circuit for the device, the switch 25 is of any usual type having four contact points. One conductor from the main supply power conduit 24 leads directly to a contact point in the switch 25. The other conductor is connected through conduit 109, to a terminal 112 carried upon the insulating panel strip 113. From the terminal 112 the conduit 88 conducts current to the contact 86 disposed within the switch 20. When the switch is in operative position, the current is then led out of the switch 20 through contact 85 and conductor 87 to a second terminal 114 disposed on the plate or panel 113.

A conductor 110 leads from the terminal 114 to one side of the fan motor 17, and a return conductor 111 leads from the fan motor 17 to a third terminal 115 disposed upon the panel 113. From the terminal 115 the conductor 116 leads to a second contact point disposed within the switch 25. The conductor 117, leading from the terminal 114, leads to the terminal bolt 106 carried by the resistance elements 95 and 96. Return terminals 118, leading from terminal bolt 107, and 119, leading from terminal bolt 108, are connected to the other two contact points of the switch 25.

When the switch is in the position shown in Figure 5, with the switch operating member 120 in a position indicated as an off position by the indicator member 121 carried upon the switch 25, the circuit is opened, and no current flows to the fan motor 17 or to the resistance elements 95 or 96. When the operating member 120 is rotated to a position ninety degrees from the position shown in Figure 5, in a clockwise direction, the switch is still in an off position, and no current flows to the device. However, when the switch member is rotated to a position corresponding to the numeral 1 on the plate 121, current flows to the fan motor and also to the resistance element 95, being conducted to this element through the conductor 117 and returned through the conductor 119.

This is the high heating position providing for rapid evaporation of the water. When the switch is rotated to a position corresponding to the numeral 2 on the plate 121, the fan motor receives 5 current and also the resistance element 96 through conductors 117 and 119. This is the low heating position, providing for slow evaporation of the water. It is to be remembered in the operation of this circuit that no current flow will occur, regardless of the position of the member 120, 10 unless the receptacle is filled with water to actuate the float for closing the circuit between the contacts 85 and 86 of the switch member 20.

In the operation of the device, the switch member 120 is first rotated to an off position, and the water is then added through inlet 48 to the chamber 56. This causes the float to rise, actuating the switch 20, and thus providing current for the fan motor 17 and for one of the resistance 20 elements 95 or 96. The switch member 120 is then turned to the desired heating position. The fan begins to draw air through the perforated cover member 41 down over the surface of the heated water, through openings 55 and out 25 through outlet 33 in the plate 11. As the water is heated, the steam or water vapor appears above the surface of the water, and is entrained by the air coming into contact therewith, the air being heated by this warm vapor. Thus, warm 30 humidified air is discharged into the room, the fan motor 17 having sufficient speed to force it to all portions of the room. When the water has reached a level determined by the position of the float 75 in contact with the stop 91, the 35 switch 20 will be automatically disconnected, thus stopping the fan motor 17 and breaking the flow of current to the resistance element. Thus the device is automatic in operation, starting only when the water has been placed in the receptacle, and shutting off when the water has 40 been exhausted, thus preventing overheating of the resistance elements.

It is thus apparent that I have provided a compact and economical air conditioning device, adapted to be embodied in an attractive portable casing, which is automatic in operation, and which may be operated for either slow or rapid evaporation of the water. The switch 25 may be placed in an "off" position when the water is added, and then manually operated to control the operation of the device. As pointed out, the device is distinctly efficient in operation because of the use of the warm or hot water principle of humidification, heating the air as it 55 passes through the steam or vapor above the surface of the water.

I do not intend to be limited to the exact details shown and described in the illustrated embodiment of my invention, but only insofar as 60 defined by the scope and spirit of the appended claims.

I claim:

1. In a portable air conditioning device, a water receptacle, a heating element in direct thermal conductive contact with the water in said receptacle and sealed in said receptacle, an air inlet for said receptacle, a fan mounted in the upper portion of said receptacle and enclosed within an annular casing communicating with 65 said receptacle, and automatic means for controlling the operation of said heating element and fan responsive to the water level in said receptacle.
2. In a portable air conditioning device, an inner casing including a water receptacle, an outer 70

casing over and about said inner casing and rigidly supporting the same, metal plates secured to said outer casing and extending thereabove, a handle secured between the extending portions of said plates, a laterally extending portion on 5 one of said plates defining an inlet for said water receptacle and serving as an air inlet to said inner casing, and an air outlet formed in said other plate.

3. In a portable air conditioning device, a water receptacle, a laterally projecting filler opening and air inlet for said receptacle, a fan for drawing air through said filler opening over the surface of the water in said receptacle and discharging it therefrom, a plurality of means for 10 heating the water in said receptacle, means for selectively connecting said heating means to a source of energy, and means controlled by the level of water in said receptacle controlling the 15 operation of said fan and heating means.

4. In combination, an inner casing, insulating material secured about the outer surface of said casing, an enclosing casing, means for securing said first casing rigidly to said enclosing casing, plate members at the front and rear of said second casing having bracket means for securing said second casing thereto, and resilient stud members threaded through said second casing and said bracket means for supporting said second casing and plate members.

5. In combination, an inner casing, insulating material secured about the outer surface of said casing, a pair of lugs extending outwardly of said casing at the top and bottom thereof, an enclosing casing, bolts extending through said lugs 35 for securing said first casing rigidly to said enclosing casing, plate members at the front and rear of said second casing having bracket means for securing said second casing thereto, and resilient stud members threaded through said second casing and said bracket means for supporting said second casing and plate members.

6. In combination, an inner casing, laterally and vertically extending means forming a spout for pouring water into said casing, a sleeve extending through the side walls of said casing adjacent the upper portion thereof and having openings communicating with the interior of said casing, a cup-shaped inner sleeve extending into one end of said first sleeve, a fan supported on 50 said inner sleeve and disposed adjacent said openings, and a grille secured over the other end of said first sleeve, said fan drawing air through said spout through the interior of said casing and said openings and discharging it out 55 through said grille.

7. In combination, an inner casing, a sleeve extending through said casing, said sleeve having openings communicating with the interior of said casing, a motor disposed concentrically within 60 said sleeve on one side of said openings, a fan operated by said motor and disposed on the opposite side of said openings, a shaft extending through the side walls of said casing and having a gravity-operated switch mounted on one end 65 thereof, means responsive to the fluid level in said casing for rotating said shaft to operate said switch, and stop means for limiting movement of said last named means.

8. In combination, an inner casing adapted to 70 contain water, a heating element disposed adjacent the bottom of said casing, a shaft extending through said casing, a switch carried at one end of said shaft and operated by rotation of said 75 shaft, means responsive to the water level in

said casing for rotating said shaft, said switch controlling the operation of said heating element, and stop means for limiting movement of said shaft rotating means.

9. In combination, an inner casing adapted to contain water, a plurality of heating elements disposed within said casing, a shaft extending through said casing, a switch carried at one end of said shaft, means for selectively connecting said switch to each of said elements, said switch controlling the energization of said elements, and means responsive to the water level in said casing to rotate said shaft for operating said switch.

10. In combination, an inner casing adapted to contain water, a heating element disposed in said casing, a shaft extending through said casing, a switch carried at one end of said shaft, means for connecting said switch to said element, said switch controlling the energization of said element, means responsive to the water level in said casing for rotating said shaft to operate said switch, and enclosing means about said casing and having a sight opening providing for observation of the operation of said switch.

11. In a device of the class described, an inner casing adapted to contain water, a heating element in said casing comprising a U-shaped member having a resistance strip therein, means for connecting said element to a source of electrical current, said element being immersed in said water to heat the same, a switch in said connecting means, and float actuated means for operating said switch to prevent overheating of said element when said water is exhausted.

12. In a device of the class described, an inner casing adapted to contain water, a plurality of heating elements immersed in said water and comprising insulated resistance members, means for selectively connecting said elements to a source of electric current, a switch controlling current flow through said connecting means, and float actuated means for operating said switch to prevent overheating of said element when said water is exhausted.

13. In a device of the class described, an inner casing, a sleeve extending through said casing, a cup-shaped supporting member within said sleeve, a motor supported on said member, a shaft extending through said member and having a fan mounted on the end thereof, a pair of plates and an enclosing member about said casing and rigidly supporting the same, a grille in one of said plates providing for ventilation of said motor, and a discharge outlet in the other of said plates concentric with said fan.

14. In an air conditioning device, a water receptacle, a float disposed therein, a shaft rotatable upon movement of said float, means for heating the water in said receptacle, and a gravity-operated switch mounted on said shaft for controlling said heating means.

15. A device of the class described comprising a water receptacle, means for admitting air over the surface of the water in said receptacle, means providing for withdrawal of said air therefrom, heating means disposed within said water receptacle, fan means providing for circulation of air across said water, an outer housing enclosing said receptacle, switch means carried by said receptacle and projecting through said outer housing for operating said fan and heating means, heat insulating means between said receptacle and housing, and means responsive to the level

of the water in said receptacle for controlling the operation of said fan and heating means.

16. In a portable air conditioning device, a water receptacle comprising a shell member having an opening in one side wall thereof above the normal water level in said receptacle, an annular chamber secured about said opening and extending into said receptacle, fan means in said chamber, communicating ports between said fan chamber and the interior of said receptacle, and an air inlet for said receptacle disposed laterally thereof whereby said fan means draws air downwardly through said inlet over the surface of the water in said receptacle and through said ports into said chamber and discharges said water outwardly through said outlet opening.

17. In a portable air conditioning device, a water receptacle comprising a shell member having an opening in one side wall thereof above the normal water level in said receptacle, an annular chamber secured to said opening and extending into said receptacle, fan means in said chamber, communicating ports between said fan chamber and the interior of said receptacle, means for heating the water in said receptacle controlled by the level of water therein, and an air inlet for said receptacle disposed laterally thereof whereby said fan means draws air from said inlet over the surface of the water in said receptacle through said ports into said annular chamber and discharges said air outwardly through said outlet opening.

18. In a portable air conditioning device, a water receptacle having an opening in one side wall thereof above the normal water level in said receptacle, an annular chamber secured to said opening and extending into said receptacle, fan means secured in said chamber, communicating ports between said fan chamber and the interior of said receptacle, means for heating the water in said receptacle, means for preventing overheating of said heating means including means responsive to the water level in said receptacle, and an air inlet for said receptacle disposed laterally thereof whereby said fan means draws air from said inlet over the surface of the water in said receptacle and through said ports into said chamber and discharges said air outwardly through said outlet opening.

19. In an air conditioning device having a water receptacle, means for heating the water in said receptacle, a restricted inlet extending laterally and upwardly from said receptacle, an unrestricted outlet above said receptacle, and a fan positioned in said outlet for drawing air through said restricted inlet across the surface of the water in said receptacle and outwardly through said outlet, the restricted inlet providing for a reduction in air pressure on the surface of the water in said receptacle during operation of said fan.

20. In an air conditioning device, a water receptacle, an outlet therefor above the surface of the water in said receptacle, a restricted filler opening and air inlet for said receptacle, and fan means in said outlet for drawing air through said inlet across the surface of the water in said receptacle and outwardly through said outlet, the relative areas of said inlet and said outlet being such as to effect a reduction in pressure on the surface of the water in said receptacle during operation of said fan means.

FRED M. OPITZ.
